UNITED STATES PATENT OFFICE.

ARTHUR M. VOGEL, OF CENTRALIA, WASHINGTON.

FLUSHING MECHANISM.

1,277,275.

Specification of Letters Patent. Patented Aug. 27, 1918.

Application filed January 17, 1917. Serial No. 142,932.

To all whom it may concern:

Be it known that I, ARTHUR M. VOGEL, a citizen of the United States, residing at Centralia, in the county of Lewis and State 5 of Washington, have invented certain new and useful Improvements in Flushing Mechanism, of which the following is a specification.

This invention relates to flushing apparatus, and more particularly has for its object 10 the provision of an automatic flushing attachment, which may be applied without alteration to the conventional form of manually operated flushing apparatus.

15 The invention has for its primary object the provision of an attachment which is simple in construction, readily applied, efficient for the purpose desired and strong and durable in use.

20 A further object of the invention, resides in the provision of a movable fluid containing cylinder, having a piston working therein and connected with the cistern, so that when the device is operated, the return of 25 the cylinder is retarded by means of the fluid contained therein.

All of the foregoing together with additional advantageous detail and arrangement of parts of the preferred embodiment of my 30 invention will be clear from a specific description hereinafter contained, when read in connection with the accompanying drawings forming a part hereof, and wherein such embodiment of the invention is illustrated for the purpose of facilitating a full 35 understanding of the present improvements.

Referring to the drawings:

Figure 1 is a side elevation showing the device attached,

40 Fig. 2 is a front elevation showing the attachment used in conjunction with a rod actuated cistern,

Fig. 3 is a detail transverse section of the actuating construction,

45 Fig. 4 is a transverse section, showing the arrangement for supporting the weighted arm, used in conjunction with the rod operated cistern, and

50 Fig. 5 is a transverse section in detail of the link connection between the actuating rod and the cistern flushing valve, as illustrated in Fig. 2.

Referring now more specifically to the drawings, and in connection with which like 55 reference characters will refer to the same

parts in the several views, 1 is a cistern, having a pipe connection 2, communicating with the flushing bowl 3, and 4 is a pivoted seat. The construction as above mentioned is of the conventional form as now being 60 used and forms no part of the present invention, with the exception that it serves as means for illustrating the arrangement of the attachment thereon.

5 is a movable cylinder, having a weight 6 attached thereto by means of a connecting rod 7 which is screw-threaded, so as to allow for the adjustment of the weight. Pivotedly secured to the cylinder is a lever 8 connected to a hinge 9 which is fastened to 70 the seat by suitable devices. 10 is a piston working within the cylinder, supplied with ports or openings 11, 12 is a piston rod attached thereto so that the piston may be actuated and 13 is a fluid contained by the 75 cylinder, such as heavy machine oil, etc. The rod 12 is connected to a chain 14 by a suitable connection arranged at 15, the chain extending to the cistern and being connected with the flushing valve. 80

In Fig. 2 I have shown a somewhat modified form, wherein the attachment is applied to a rod actuated cistern, and in this particular construction, 1' is a cistern, connected with the flushing bowl 2', 3' is a movable cylinder supplied with the weight 4', and the flexible connecting member 5' which is connected at 6' to the piston rod. The construction of the attachment as thus far described, is identical to that used in the 90 prior embodiments. The supplemental attachment used with the rod actuated cistern, consists of a weighted arm 7; connected at one end with the flexible member 5', which is pivotally supported at 8' and supplied 95 with a weight 9', which weight is supported by a bracket member 10'. Connected with the pivoted arm 7' is an actuating rod 11' carried by a pivoted link portion 12' for operating the flushing valve. 100

It will be seen that the operation of the attachment as shown in Fig. 1 is as follows:—Assuming that the seat 4 is down, the movable cylinder with its weight 6 will be held out of engagement with the floor, thereby causing a slack in the flexible member 14, which is gradually taken up by the descent of the piston 10 into the fluid 13, the fluid passing through the ports 11 into a position over the piston 11, whereupon 110

the piston is stopped in its downward movement by means of the flexible member 14. When the seat is released and allowed to be swung upward, the cylinder 5, will be 5 abruptly lowered, thereby causing the piston 10 to be carried with the same, which action, will cause the flexible means 14 to actuate the flushing valve. The piston 10 is slowly retracted, the fluid 10 passing back 10 through the ports 11 to the bottom of the cylinder 5 and when so arranged is ready for the next operation.

Referring to the modified form as shown in Fig. 2, it may be stated that the operation 15 thereof is the same as that above described, but in order to provide for means of sufficient weight for retracting the piston, there is provided the weighted arm, which by reason of the weight 9', will cause the piston 20 to be slowly retracted. Such a construction may be also used in other cisterns wherein the siphon is not of sufficient weight to retract the piston.

In accordance with the patent statutes, I 25 have described the principle of the invention, together with an apparatus which I now consider to represent the best embodiment thereof, but I desire to have it understood, that the apparatus shown may be subjected to different arrangements of parts 30 from those herein shown and described, for producing the desired results, together with mechanical equivalents for some or all of the said parts.

35 Having thus described the invention, what I claim is:—

1. In a flushing mechanism of the character described, the combination of a movable cylinder, a connecting rod secured to said cylinder, a weight adjustably mounted upon the lower end of said rod, said cylinder being adapted to contain a quantity of heavy fluid matter, a piston rod projecting into the upper end of said cylinder, a piston carried upon the inner end of said rod and having ports formed therein, said piston rod being adapted to be connected to a valve mechanism, means for raising said cylinder and weight and holding the same in elevated position for a predetermined time, whereby said piston rod and said piston will move downwardly toward the lower end of said cylinder, while the fluid will pass through said ports above said piston, and 55 said cylinder being adapted to be lowered suddenly thus causing the weight of the fluid upon the piston to draw downwardly upon the piston and piston rod for tripping a valve mechanism, although said fluid will 60 gradually pass through said ports below said piston.

2. In a flushing mechanism of the character described, the combination of a cistern having a valve mechanism, a flushing bowl, 65 means connecting said cistern to said bowl,

a seat hingedly mounted upon said bowl, a hinge secured to said seat and projecting therebeyond, a lever pivotally mounted upon said hinge and projecting therebelow, a cylinder hingedly secured to the free end 70 of said lever, a rod connected to said cylinder, a weight adjustably mounted upon said rod, whereby said cylinder and weight will normally draw downwardly upon the lever for elevating the seat for a predetermined 75 distance, a piston rod extending into the upper end of said cylinder, a piston carried upon said rod, said piston having ports formed therein, said cylinder being adapted to contain a quantity of comparatively 80 heavy liquid material, whereby as said seat is pressed into a substantially horizontal position said hinge and lever will lift said cylinder and weight, thus allowing the piston rod and piston to gradually settle toward the lower end of said cylinder by the 85 passage of the liquid through said port, and said weight being adapted to abruptly draw the cylinder downwardly when the pressure is removed from the seat, thus exerting a 90 pull upon said piston rod, said piston rod being adapted to be connected to the valve mechanism of said cistern, for actuating the same as it is moved.

3. In a flushing mechanism of the class 95 described, the combination of a movable cylinder, a piston rod projecting into said cylinder, a piston carried upon the inner end of said rod and having ports formed therein, said piston rod being adapted to be connected to a valve mechanism, means for raising said cylinder and holding the same in an elevated position for a predetermined time, thus allowing said piston rod and said piston to move downwardly toward the 100 lower end of said cylinder, while the contents of the cylinder will pass through said ports and said cylinder being adapted to be lowered suddenly, thus causing the contents of the cylinder to force the piston downwardly for tripping a valve mechanism, although said contents will gradually pass through said ports below said piston.

4. In a flushing mechanism of the character described, the combination of a cistern 115 having a valve mechanism formed therein, a flushing bowl, means connecting said cistern to said bowl, a seat hingedly connected to said bowl, a hinge secured to said seat and projecting therebeyond, a lever pivotally mounted upon said hinge and projecting therebelow, a cylinder hingedly secured to the free end of said lever, said cylinder normally drawing downward on said lever 120 for elevating the seat for a predetermined distance, a piston rod extending into the upper end of said cylinder, a piston carried upon said rod, said piston having ports formed therein, whereby as seat is pressed into a substantially horizontal position, said 125

lever will lift said cylinder, thus allowing the piston rod to gradually settle toward the lower end of the cylinder by the passing of the contents of the cylinder through said 5 ports, and said cylinder drawing downwardly suddenly when pressure is removed from the seat, thus exerting a pull upon said piston rod, said piston rod being connected to a valve mechanism of said cistern, for ac-

tuating the same when said cylinder is lowered.

In testimony whereof I affix my signature in presence of two witnesses.

ARTHUR M. VOGEL.
